UNITED STATES PATENT OFFICE.

MATTHEW J. KONOLD, OF PITTSBURGH, PENNSYLVANIA, AND RALPH T. PRALL, OF YOUNGSTOWN, OHIO.

STEAM-TRAP.

1,119,286.

Specification of Letters Patent.

Patented Dec. 1, 1914.

Application filed January 30, 1911. Serial No. 605,589.

To all whom it may concern:

Be it known that we, MATTHEW J. KONOLD, residing at Pittsburgh, Pennsylvania, and RALPH T. PRALL, residing at Youngstown, in the county of Mahoning and State 5 of Ohio, citizens of the United States, have invented or discovered certain new and useful Improvements in Steam-Traps, of which improvements the following is a specification.

In the construction of machines or tilting vessels, such as are commonly known as gravity, tilting, steam, return, or vacuum traps, or any other machines wherein a fluid gains entrance to a receptacle mounted upon a trunnion, or other pivoted support, it has been customary to gain entrance to the receptacle directly through the trunnions, to the end that the pivotal movement of the receptacle will not be impeded. To accomplish this entrance, the trunnions have been provided interiorly with openings, and the connection to these openings have required packed joints, a feature that 25 has interfered with, and hence made uncertain, the tilting action of the receptacle. Since the operation of traps, such as have been heretofore mentioned, is entirely dependent upon the tilting of the receptacle, 30 upon the collection of a predetermined amount of water, the freedom of motion of the trunnion is a matter of vital importance.

Our invention relates to machines of the character described, and the object of our 35 invention is to provide an entrance to the receptacle in a manner that will not interfere with the free movement of the trunnions in their bearings and in a manner that will permit of the use of bearing elements, 40 such as roller or ball bearings.

A further object of our invention is to construct tilting receptacles in such a way that their emptying will be more nearly complete.

45 Since our invention finds application in a steam-trap, we choose to describe it therewith, but we do not wish to limit ourselves to such application, for obviously it can be used in various other devices.

50 In the accompanying drawings, which form a part of this specification, Figure 1 is a side elevation and Fig. 2 is an end view of a steam-trap embodying our invention, and Fig. 3 is a partial end view showing 55 the lever connection to the escape pipe. In

these figures like numerals are used to designate like parts.

In the operation of steam-traps of the character described, water gains entrance to a pivoted receptacle through a pipe-section, 60 which, besides being a conduit, is also a support for the receptacle. A second support for the receptacle is provided, which yields under a predetermined weight, and this feature is conveniently embodied in a weighted 65 lever which holds the receptacle in such a position (usually horizontal) that the water will not flow therefrom until a predetermined weight has gathered therein, which weight is sufficient to counterbalance the 70 weighted lever and cause the support to yield. The receptacle, when it tilts, opens a valve to permit of the escape of the water contained within the receptacle, and, when all or part of the water has escaped therefrom, the yielding support becomes again 75 effective to swing the receptacle back to normal position and sustain it there until water has again collected in it to the critical amount. 80

In the particular steam-trap shown in the drawings, and in which our invention finds application, the water of condensation is taken by the inlet conduit 20 from the steam line, or from a separator, or other receptacle 85 provided for its collection, and gains entrance to the receptacle 1 through an inwardly extending pipe 2, which pipe has connection to the inlet conduit preferably through the flexible hose 9 and the manifold 90 3. The water gathered in the receptacle flows therefrom, preferably through the pipe 5, the manifold 3, and the flexible hose 9^a to the escape conduit 21. The pipe 2, being secured to the manifold 3, which in turn 95 is suitably provided with trunnions 22, also forms a support for the receptacle 1, and is conveniently located at one side of its center of gravity. A second and movable support for the receptacle is conveniently provided at the other side of its center of gravity by means of a lever 4, one end of which engages a laterally extending arm of the pipe connection 18 through the link 19 and holds the receptacle yieldingly against the stop 12. 100

The lever 4 is pivoted at 17 upon a support 6 and may be weighted at its other end by a movable block 7, conveniently carried by the roller 13, to the end that, when the weighted arm of the lever rises, in conse- 110

quence of the tipping of the receptacle, the weight will move away from the stop 15 and toward the fulcrum point 17, and thereby exercise less effect to cause the receptacle 5 to return to a horizontal position. The location of the pivot point 17, with reference to the longitudinal extent of the lever may be ascertained by taking into consideration the weight of the block 7 and the capacity 10 and construction of the receptacle, to the end that the said receptacle will be held in fixed filling position both when empty and until a predetermined amount of water shall have collected therein.

15 It will be understood that, when the receptacle tilts, the weighted end of the lever will rise, the weight will move toward the fulcrum point and the rotation of the receptacle will be limited by the stop 11. Furthermore 20 the fluid content will move away from the pivot support of the receptacle, and, in consequence thereof, a greater portion of the load will be acting against the lever 4 to hold its weighted end in elevated 25 position. This shifting of the center of gravity of the supported partially-filled receptacle will insure an appreciable emptying of its contents, which is made nearly complete by the proper disposition of the 30 stop 15^a, which limits the forward movement of the block 7. Simultaneously with the tilting of the receptacle suitable means are provided for opening an escape conduit for the water contained therein. As shown 35 herein the discharge pipe 21 is provided with a valve 8, which may be opened by a suitable arm 14, secured to the outlet pipe 5 to the end that, when the receptacle drops, the lower end of the arm will open the said 40 valve and keep it open until the receptacle rises.

As heretofore stated, the freedom of motion of the trunnion is of great importance in order to insure an emptying of the receptacle when a certain amount of water has 45

collected therein. To insure an unimpeded movement of the receptacle we provide the standard 10 with suitable bearing elements, as ball or roller bearings, and this construction is made possible since we connect the 50 entering and discharge conduits to the trunnions, preferably with flexible hose, and thereby eliminate the necessity of a packed joint. The trunnion is provided with the double manifold passage-way 3 to the end 55 that water may enter the receptacle through the supporting pipe 2 and may flow therefrom through the pipe 5. Furthermore, in order to diminish the amount of flexure of the hose connection, incident to the tipping 60 of the receptacle, we preferably form depending arms on each end of the manifold 3, and to these arms we secure the trunnions 22, which trunnions, it will be understood, move pivotally in the supports 10, 65 and have their center of rotation below the center of the manifold to most effectually accomplish this end.

We claim as our invention:

In a steam trap, the combination of a 70 pivotally supported manifold member, an inlet conduit leading from one passageway of said manifold member to a receptacle and forming an eccentrically disposed support for said receptacle, an outlet conduit 75 connecting a second passageway of said manifold member to the said receptacle, feed pipes leading to and escape pipes leading from said receptacle, and flexible pipes connecting said feed and said escape pipes 80 with the said manifold passageways, substantially as described.

In testimony whereof we have hereunto set our hands.

MATTHEW J. KONOLD.
